John Phelps Marr
ATTORNEY

UNITED STATES PATENT OFFICE

SAMPSON BROADWIN, OF BROOKLYN, NEW YORK

PATTERN MECHANISM FOR CROCHET KNITTING MACHINES

Application filed November 14, 1929. Serial No. 407,068.

The device, the subject of this invention, is a pattern mechanism, and more particularly the chain operation of that mechanism, and the object of the invention is to provide 5 a chain wherein the pins may be very readily changed.

Another object is to provide means for limiting the wear of the pins, and another object is to provide means whereby the pins 10 are retained reliably in position, and yet under such conditions that they may be withdrawn, and a new pin inserted, and at will.

The following is what I consider the best 15 means of carrying out my invention, and the accompanying drawings should be referred to for a complete understanding of the specification which follows.

In the drawings:—

- 20 Fig. 1 is a plan view of a single link,
- Fig. 2 a side elevation thereof,
- Fig. 3 a sectional view of the link, with a pin in position,
- Fig. 4 a plan view of a plurality of links,
- 25 Fig. 5 an enlarged view of a pin, and
- Fig. 6 an enlarged sectional view of a socket.

Similar reference numerals indicate like parts in all the figures where they appear. 30 The links of my device will be formed of cast aluminum, and I prefer the use of such material. Each link is an oblong member having a plurality of bosses extending upon one side of the link. The bosses are shown 35 at 1, 2, 3, 4, 5, 6, 7 and 8, and while I have shown eight bosses, I have shown them merely because of the reason that the link that I have shown is a standard link, and eight pins are usually provided in a standard link.

40 The bosses are each drilled for the reception of socket members, the socket member being arranged in each boss, and projecting upward therefrom. These socket members, which should be of steel, are forced into properly prepared holes in the bosses. The socket members are indicated at 9, 10, 11, 45 12, 13, 14, 15 and 16.

Each link is provided with a plurality of lugs, and it will be noted that the space between the lugs 17 and 18, is greater than

the space between the lugs 19 and 20. The lugs are perforated for the reception of adjoining pins, as shown at 21 and 22, and these pins may each be provided with a cotter pin, as shown at 23 and 24.

The reason for the difference in spacing of the lugs is fully demonstrated in Fig. 4 of the drawing, the lugs 17 and 18 ending outside of the next progressive lugs 19 and 20 of the next progressive link.

The ribs, as shown at 25, and extending between the bosses are strengthening ribs only.

I call special attention to the socket members, one of which is shown in enlarged section, in Fig. 6. This socket member is provided with a perforation 27, having an enlarged diameter at the lowermost end, as shown at 28.

The pin shown in Fig. 5, is provided with 70 a slot 29, extending inward from the lower end thereof. At the lower end, I provide a ball portion 30, and a steel washer 31 resting upon a shoulder 32, is retained upon the small portion 33 of the pin 34 by the 75 expansion of this portion, due to the slot 29. The washer is of a diameter about equal to the top of the socket, and serves to prevent undue wear, because of the operative pressure which is applied to the top 26 of the 80 pin 34.

It will of course be understood that pins of different lengths are provided, and that my device is so constructed that different length pins can be substituted readily, and 85 yet in such a manner that the pin will be reliably held in its socket, except when forcibly removed therefrom.

In Fig. 3, I show only one pin in position, but it will of course be understood 90 that pins may be inserted into all or any of the sockets, as shall be required by the particular pattern which it is desired to produce.

For ease of insertion of the pins, the ends 95 of the sockets may each be counter-sunk, as shown in Fig. 3.

If the link is formed as a die casting, the sockets may be formed integral therewith.

Having carefully and fully described my 100

invention, what I claim and desire to secure by Letters Patent is:—

1. In a pattern mechanism for crochet knitting machines, a plurality of links, bosses formed thereon, a socket engaged in each said boss each said socket having a perforation of two diameters extending therethrough, a pin arranged in each said socket, each said pin being provided with an expansible means for retaining the pin in the socket and an enlarged head adapted to engage in that part of said perforation having the larger diameter.
2. A pattern mechanism for crochet machines, including a socket provided with a perforation having two diameters, a pin adapted to be received in said perforation, said pin being provided with an elongated saw-kerf, a wear disk upon said pin and away from both ends of said saw-kerf.
3. In a pattern mechanism for crochet machines, a pin formed of two or more diameters, a saw-kerf in a small diameter and extending into a larger diameter, a wear plate upon said pin and in combination therewith, a socket provided with a perforation having two diameters, the enlargement of said pin being adapted to engage in said larger diameter, to be retained therein.

SAMPSON BROADWIN.
